UNITED STATES PATENT OFFICE.

PAUL HARTMANN, OF BERLIN, GERMANY, ASSIGNOR TO THE FIRM OF HOCHSTEIN & WEINBERG, OF BERLIN, GERMANY.

DEVICE FOR FEEDING SHEETS.

974,767.

Specification of Letters Patent.

Patented Nov. 1, 1910.

Application filed July 20, 1910. Serial No. 572,812.

To all whom it may concern:

Be it known that I, PAUL HARTMANN, a subject of the King of Prussia, and resident of Berlin, German Empire, have invented 5 certain new and useful Improvements in Devices for Feeding Sheets, of which the following is a specification.

The invention relates to an improved device for feeding sheets one by one from a pile. This improved device is applicable to a pasting machine with a continuous drive which in particular may be adapted for covering paste-boards of different sizes. In such a machine the boards or sheets to be 15 covered may be fed by hand or the machine may be arranged to coöperate with a mechanical device of any suitable type for feeding the paste-boards or sheets to be covered in which case the movements of the machine 20 should be dependent upon those of the feeding device.

One form of carrying the subject matter of the present invention into effect is illustrated diagrammatically in the accompanying drawings as applied to such a pasting machine, Figure 1 being a side view, Fig. 2 a plan, Fig. 3 a section on the line A—B of Fig. 2 and Fig. 4 a view looking in the direction of the arrow in Fig. 1.

Referring to Figs. 1 to 4 of the drawings, 30 1 is a table provided with a vertical to-and-fro-movement, upon which the material 2 is piled which is intended to be pasted over the paste-boards. The table 1 is capable of 35 sliding vertically. In Fig. 1 the table is shown in the lowest position. A weight 3 however which is attached by a cord at a point 5 to the table and passes over a roller 6 tends to raise the table 1. The raising of 40 the table is opposed by a cord or the like 7 which is attached at 8 to the table and at 9 to a reciprocating box 10 after passing over a fixed roller 11.

The box 10 is connected with rollers 12 45 and 13 in such a manner that the parts 10, 12 and 13 combined, form a frame which swings about an axis 14. The under surface of the box 10 is perforated, as can be seen in Fig. 3. A traveling cloth of felt or 50 other suitable material permeable to air is stretched over the rollers 12 and 13.

The frame which is formed by the parts 10, 12, 13, 15 can be rotated about its axis, according to the constructional form given 55 by way of example, by means of a lever 16,

provided with a weight 17 which can be raised by a hand lever 26 and connecting cord. When the lever 16 is raised, the whole frame with the box 11 falls as according to the constructional form illustrated as an example, the influence of the weight 17 is annulled. During this movement the point 9 also falls so that the cord 7 permits the table 1 to yield to the influence of the weight 3 tending to raise it. As therefore the box 60 10 owing to the rotation of the whole frame falls toward the horizontal position, the table 1 rises so that both parts come into contact, as shown in dotted lines in Fig. 3.

The box 10 serves for raising the piled 70 material on the table 1. To this end a partial vacuum is maintained in the interior thereof. According to the constructional form selected for illustration this takes place through a vibrating branch 18 of a vacuum 75 pipe arranged centrally with respect to the axis 14. As the result of this partial vacuum which is communicated to the pile of material through the felt band 15 the uppermost leaf adheres to the felt band. The 80 felt band receives its movement from driving gear, for example from a constantly rotating wheel 20. A chain or cord 21 as shown being carried over a driving pulley 30 on the spindle of the roll 12 and a pulley 85 48. The movement of the felt band 15 does not commence, as will be described later, until the box 10 has been raised clear of the table 1, that is to say from the pile of paper material. The sheet to be pasted on 90 the paste board adhering to the under side of the felt band 15 is carried thereby and delivered to the delivery rolls 22. To insure this delivery, a further device is provided. A guide 24 provided with crank 95 lever 25 and rotating about an axis 23 is provided which yields as the parts 10, 12 and 13 fall, as shown in dotted lines in Fig. 3. When the parts again rise, the spindle of the roll 13 which is extended sidewise, 100 strikes the lever 25. Thereby the lever 24 is brought to bear evenly against the under surface of the web 15 and affords the strip of material fed by this web a good support until it is gripped by the delivery rolls. In 105 the moment in which the under portion of the traveler 15 sinks upon the rising pile of material the movement of the traveler as already mentioned is stopped. This takes place in the following manner:—As soon as 110

the lever 16 by operating the hand lever 26 has been raised, it strikes a crank arm 27. To this crank arm a bar 28 is connected the free end of which is coupled to the movable portion 29 of a coupling which is normally held in gear by a spring 31. The coupling member 29 carries the driving wheel 30 for the roll 12. So long therefore as the lever 16 is raised, the driving, by means of the chain or rope 21, of the roll 12 and therefore that of the traveling band 15, ceases. As soon however as the lever 16 again falls, the spring 31 presses the coupling again into gear and the movement of the traveler immediately recommences. By this time the partial vacuum in the box 10 has caused the top sheet of the material to be lifted vertically from the pile. The sheet as it is further fed forward is soon supported by the guide 24, and in this way is conducted to the delivery rolls 22. The single sheet lifted from the feeding pile is transferred by the delivery rolls 22 to the roll 33 which is covered with adhesive substance through the medium of an intermediate roll 32. Both rolls receive constant movement from the driving wheel 19. A suitable guiding device 34 which may consist of a suitably shaped scraper or a longitudinal series of scrapers insures the removal and reversal of the paper sheet, after reception of the adhesive substance, and the transfer of the same to a traveling web 35. The traveling web 35 passes around rollers 59, 60, 61 and 62 and above a box 36, the upper surface of which, as can be seen from Fig. 3, is partly perforated, while a partial vacuum is maintained in the interior.

According to the constructional form selected for illustration the rarefaction of the air takes place through a branch 37 of the vacuum pipe. At the rear end of the traveling band 35, rolls 38 and 39 are mounted in bearings, the speed of which is greater than that of the traveling web 35. Upon the rolls 38, 39 are mounted strips of india rubber 40, 41 which also pass over rollers 42, 43 mounted in bearings in receptacles for water 44, 45. Rearward of the rolls 38, 39 are located rolls 46, 47, covered with felt or other suitable material and rotating in the same direction as the rolls 38, 39.

The operation of the constructional form of the machine which has been selected for illustration is as follows:—The driving wheel 20 continuously revolves and thereby operates the rolls 32 and 33. This operation is transferred to the driving wheel 30 for the traveling band 15 and also to the roller 59 for the traveling band 35 through the driving wheel 48, from the spindle of which by means of the driving wheels 49, 50, 51, 52 and the chains or ropes 54, 55, the roll 39 is driven and also the roll 38 through

the connecting wheels 56, 57. The delivery rolls 22 are connected together by gearing not shown and are driven by a crossed strap 58 from a pulley 53 on the spindle of the roll 38. All these parts are in movement until, as is now to be assumed, the lever 16 by means of the handle 26, has been raised and thereby the traveler 15 with its vacuum chamber 30 has been lowered by its own weight. As soon as the under portion of the traveling band 10 has reached the horizontal position, the lever 16 by means of the parts 27 and 26 has uncoupled the coupling 29 which drives the traveling band 15 by means of the driving pulley 30. The sucking up of the top sheet from the pile of material takes place while the traveling band 15 is at rest. When the top sheet of the pile of material has been sucked up, the hand lever 26, according to the example illustrated is again released. Thereupon the lever 16 falls which entails an upward swinging movement of the traveler 15, whereupon the axle of the roll 13 of the traveler strikes against the lever 25, so that the lever 24 swings out against the traveler and, owing to the simultaneous commencement of the movement of the traveler as the result of the coupling 29 being again thrown into gear, the sheet, which has been sucked up, is provided with a positive guide until gripped by the delivery rolls 22. It is then passed in a manner which is not further illustrated, around the circumference of the roller 33 which is covered with adhesive substance, its direction of movement is reversed by the device 34 and it is then delivered upon the traveling band 35. The delivery upon the traveling band is insured by the first portion of exhaust holes in the vacuum box 36. The box is not provided with exhaust holes under the center portions of the traveling band 35. The object of this arrangement is to leave the strips provided with adhesive substance for a certain length of time uncontrolled so that especially sidewise the sheet may be free to extend according to the amount of moisture received. At the rear of the feeding band 35 the sheet is again sucked down and in this condition arrives at the quicker traveling rolls 38, 39. The object of this arrangement is to paste the sheet upon the paste board in a stretched condition and free from blisters. The rollers 38, 39 are provided with an india rubber covering which has been wetted by water, in order to avoid spreading of any of the adhesive substances which may have been pressed out. Such surplus paste will be softened in the water receptacles and removed by suitable scrapers. As the first pair of rolls may be insufficient to effect the perfect adhesion of the two parts to be secured together rollers 46 and 47 covered with stretched felt or the like are further provided.

For the sake of simplicity in the illustration and for the sake of clearness in the specification the delivery device for the pasteboards to be covered has been only referred to in general terms and represented in the drawings by the arrow shown in Figs. 1 and 3. In fact the delivery device may be of any suitable construction. It is essential however for the purpose that the 10 mechanism of the feeding device should be dependent upon that of the machine for delivering the sheets to be laid on or vice-versa.

The operation of the hand lever 26 and 15 the return movement of the same into normal position must necessarily arrest the movement of the delivery device, so that a paste board is conveyed in such a manner that it arrives at the same time at the rolls 20 38, 39, as the sheet which by operation of the hand lever 26 has been delivered to the delivering web 15 and then supplied with adhesive substance. Equally well the throwing into gear of the whole mechanism can 25 take place through the paste board delivering device in which case the delivery of the sheet to be pasted on by the delivering web 15 must take place when the delivery mechanism of the paste board delivery device is 30 set in motion.

A very important advantage of the machine when combined with a sheet laying on device is that paste board of any size can be worked up with the same machine without 35 waste. The manufacturer is also in a position to carry out quite small orders which previously were not worth the trouble as either special machines were required or important alterations in the machine were necessary. 40

For the laying on of the sheets it is intended in particular to employ an arrangement adapted to coöperate with the arrangement for delivering the sheets supplied with 45 an adhesive substance which effects the delivery in exactly the same manner as with the sheets to be pasted on. In this case therefore the raising of the sheets can be also effected by a reciprocating frame under 50 the influence of a partial vacuum from a table which is dependent as to its movements upon those of the frame.

It is especially to be noted that the details of the driving arrangements are indicated purely diagrammatically and described in general terms and that the construction may be altered in any desired manner without passing the sphere of protection of the invention. For instance in carrying 60 the invention into practice the reciprocating table is preferably nearly balanced by a weight which may be mounted upon one end of a pivoted lever the other end of which engages with the table or an 65 extension thereof. The weight is or can be

so adjusted that the table with the pile of sheets thereon always has a tendency to rise. To arrest the upward movement of the table a stop is provided. The stop is adapted to engage either with the top of 70 the pile of paper or with the table itself in which latter case the height of the stop is constantly regulated and adjusted by the depth of the pile of material on the table.

In order to avoid too great a drag on the 75 top sheet as it is withdrawn from the pile the stop is preferably adapted to be raised clear of the sheet as this is withdrawn from the pile, and to be returned to normal position after withdrawal of the sheet. In order 80 to retain the table in the position in which it was arrested by the aforesaid stop a locking device is provided which is adapted to lock the table prior to the raising of said stop and to unlock the table after the return of 85 the stop to normal position. Such a locking device may consist of a pin provided with a screw thread which is automatically rotated in one direction or the other so that the table may be alternately held by pressure 90 and released. Further the frame which carries the suction box 10 and the rollers for the traveling web 15 may be partly balanced by a weight and the frame lowered against the influence of the weight or vice versa by a cam 95 mounted on a shaft arranged transversely with respect to the direction of travel of the web 15. Also the coupling and uncoupling of the roller 12 may be effected automatically by utilizing the reciprocating movement of the aforesaid frame, for instance by means of a cam path arranged concentrically with the roller 12, extending parallel to the axis of said roller and adapted without rotating to slide axially while in engagement 100 on the one hand through antifriction devices with the movable spring actuated portion of a coupling and on the other hand with a part which may be provided with rollers and which rotates synchronously with said frame so that said coupling portion is moved 105 against the influence of said spring into gear with the driving or driven member and alternately released. With this arrangement the roller 12 may be rotatably mounted on a 110 main vacuum pipe supported in the frame of the machine in which case the branch pipe 18 is rotatably mounted about the main vacuum pipe and the main vacuum pipe is provided with a suitable port or ports affording communication between the main pipe and said branch pipe. In this case the aforesaid cam path may be arranged on a disk mounted on said main vacuum pipe by means of a feather and featherway adjacent 115 to said branch and the coöperating part rotating with the suction box and provided with rollers may be mounted on a sleeve formed on said branch pipe and surrounding the main vacuum pipe. Further the 120 125 130

- coupling and the continuously rotating gear wheel 30 may be mounted on a sleeve or extension of the roller 12. The center of the roller 12 may be raised so as to be clear of the pile of material on the table 1 when the traveling web 15 is in contact therewith an additional roller being provided between the roller 12 and the suction box 10 to maintain the desired angle of the traveling web 15.
- 10 Adjustable devices may be provided for regulating the angle of the traveling web 15. Adjustable devices may be provided for regulating the tension of the web 15. Adjusting devices for regulating the tension of the other traveling webs belts or the like are preferably introduced when required or found desirable.

Instead of providing chain or belt drives interchangeable gear may be introduced so as to enable the speed of travel of the webs to be varied as required. To facilitate the changing of the gear horizontal cross girders are provided connecting the end standards of the machine and the cross girder is provided 25 preferably with longitudinal channels in which the bearings for the spindles of the gear wheels may be adjustably secured. The aforesaid stop and locking devices for the table 1 may be conveniently driven by cam 30 devices mounted on or receiving their motion from the aforesaid transverse cam shaft for causing or permitting the reciprocation of the suction box 10 and the traveling web 15.

35 In the case of combined machines for automatically delivering simultaneously the two sheets to be pasted together both machines may be driven by the same motor and in order to regulate the speed of one 40 machine relatively to the speed of the other machine a variable speed gear capable of fine adjustment may be introduced between the two machines. Such a variable speed gear may be of any well known construction as for instance two slightly oppositely coned pulleys a connecting driving belt and means for varying the portion of the belt or a right-angled drive may be employed with means for varying the position of one member 45 of said drive with respect to the center of rotation of the other member of the drive.

I claim:—

1. Feeding apparatus for sheets comprising a reciprocating perforated vacuum chamber, 55 means for rarefying the air in said chamber and a permeable web traveling over the perforated wall of said chamber so that the sheet is held on the web by atmospheric pressure.
- 60 2. In a feeding apparatus for a sheet pasting machine the combination with means for removing the sheets one by one from a pile means for supplying the sheet when removed with an adhesive substance and drawing rolls, of a traveling device adapted to con-

vey the sheet by suction when supplied with the adhesive substance to said drawing rolls said device having a lesser speed than the surface speed of said rolls whereby the trailing end of the sheet is yieldingly retarded for the purpose set forth. 70

3. Feeding apparatus for sheets comprising a permeable traveling web adapted to be reciprocated to and from the pile of sheets, means for subjecting said web to the influence of a partial vacuum, means for reciprocating said web and means dependent upon said reciprocating means for causing said web to travel to deliver the sheets. 75

4. Feeding apparatus for sheets comprising a permeable traveling web adapted to be reciprocated to and from the pile of sheets means for subjecting said web to the influence of a partial vacuum, means for reciprocating said web and means dependent upon said reciprocating means for causing said web to travel to deliver the sheets whereby the traveling movement of said web ceases as soon as said web sinks to the supply pile of sheets, so that the removal 85 of the top takes place while said web is at rest. 90

5. In a feeding apparatus for a sheet pasting machine, the combination with means for removing the sheets one by one from a pile 95 means for supplying the sheet when removed with an adhesive substance and drawing rolls, of a traveling device adapted to convey the sheet when supplied with the adhesive substance to said drawing rolls by suction, means for rarefying the air through 100 said device at the receiving and delivery ends thereof said device having a lesser speed than that of the surface speed of said rolls whereby the sheet in part is yieldingly retarded in opposition to the influence 105 of the drawing rolls and in part is free to deform under the influence of the moisture due to the adhesive substance. 110

6. A feeding apparatus for sheets comprising an air chamber having the lower wall perforated, means for rarefying the air in said chamber, a web permeable to air adapted to travel in contact with the lower perforated wall of said chamber, means for moving simultaneously said web and said chamber into contact with and away from the pile of sheets to be fed, means for causing the longitudinal movement of said web and a coupling controlled by the second- 115 named means for connecting and disconnecting the last-named means. 120

7. A sheet pasting machine comprising a reciprocating table for the sheets to be pasted an air chamber having the lower wall 125 perforated, means for rarefying the air in said chamber a web permeable to air adapted to travel longitudinally in contact with the lower perforated wall of said chamber, means for moving simultaneously said web 130

and said chamber into contact with and away from the pile of sheets on said table, means for raising said table in synchronism with the falling movement of said web,
5 means for moving said web longitudinally, means whereby the longitudinal movement of said web is arrested as it falls into contact with the top sheet of the pile, pasting means adapted to receive the sheet as it is delivered by the longitudinal movement of said web, a second traveling web permeable to air means for delivering the sheet when pasted upon said second web, a second air chamber having a perforated wall in contact with said second web means for rarefying the air in said second chamber, pressure and drawing rolls located at the delivering end of said second web, means for causing longitudinal movement of said second web, means for rotating said rolls at a greater rate of speed than that of the speed of the longitudinal movement of said second web and means for automatically delivering to said rolls a sheet synchronously with the delivery of the pasted sheet.

8. A sheet pasting machine comprising a reciprocating table for the sheets to be pasted, an air chamber having the lower wall perforated, means for rarefying the air in said chamber, a web permeable to air adapted to travel longitudinally in contact with the lower perforated wall of said chamber, means for moving simultaneously said web and said chamber into contact with and

away from the pile of sheets on said table, 35 means for raising said table in synchronism with the falling movement of said web, means for moving said web longitudinally, means whereby the longitudinal movement of said web is arrested as it falls into contact with the top sheet of the pile, pasting means adapted to receive the sheet as it is delivered by the longitudinal movement of said web, a second traveling web permeable to air, means for delivering the sheet when 40 pasted upon said second web, a second chamber having a wall perforated toward each end in contact with said second web, means for rarefying the air in said second chamber, pressure and drawing rolls located at the 45 delivering end of said second web, an endless band surrounding at one end each of said rolls, a receptacle for liquid for each set of bands, a roller located in each receptacle for the other ends of said bands, means for causing longitudinal movement of said second web, means for rotating said rolls at a greater rate of speed than that of the speed of the longitudinal movement of said second web and means for automatically delivering 50 to said rolls a sheet synchronously with the delivery of the pasted sheet.

In witness whereof I have hereunto set my hand in the presence of two witnesses.

PAUL HARTMANN.
